SHAKER CONVEYER

William W. Sloane, Chicago, Ill., assignor to
 Goodman Manufacturing Company, Chicago,
 Ill., a corporation of Illinois

Application October 5, 1939, Serial No. 298,016

7 Claims. (Cl. 198—220)

This invention relates to improvements in shaker conveyers, and more particularly to an adjustable trough supporting and aligning means for a shaker conveyer trough line, adapted to be secured between a mine floor and roof to hold the trough line in longitudinal and transverse alignment.

The principal objects of my invention are to provide a new and improved adjustable trough supporting and guiding means for a shaker conveyer trough line including a plurality of spaced apart supporting jacks having trough supporting rollers mounted thereon in such a manner that the trough line may readily be aligned and held in both vertical and horizontal alignment during operation of the conveyer, when the jacks are in various angular positions with respect to each other, together with a simple means for adjusting the rollers and their supporting shafts along the jacks.

My invention may be more clearly understood with reference to the accompanying drawing wherein:

Figure 1 is a view in side elevation of a part of a shaker conveyer trough line, supported by trough supporting means constructed in accordance with my invention;

Figure 2 is an enlarged transverse sectional view taken through the trough line, showing certain parts of one jack broken away and certain other parts thereof in transverse section;

Figure 3 is an enlarged fragmentary isometric view, showing one of the trough supporting jacks and the supporting connection from this jack to the conveyer trough; and

Figure 4 is an enlarged detail view showing certain details of construction of the adjustable supporting connection for the trough supporting roller on its supporting jack.

Referring now to the embodiment of my invention illustrated in the drawing, a shaker conveyer trough line generally indicated by reference character 10 is shown as being supported and guided on a plurality of pairs of spaced apart jacks 11, 11, interposed between a mine roof and floor. Said shaker conveyer trough line includes a plurality of trough sections 12, 12 connected together at their ends by connecting bolts 13, 13 extending through abutting eye pieces 14, 14. Said trough line is reciprocably driven by the usual type of reciprocable drive mechanism (not shown), in such a manner that reciprocable movement of said trough line will cause material to move therealong in one direction.

The jacks 11, 11 are of a usual construction,

each consisting of a sleeve 16 mounted on a foot 17, adapted to engage the ground. A collar 18 is secured to the upper end of said sleeve. A threaded shaft 19, having a cap piece or roof-engaging member 20 on the upper end thereof, is adapted to extend within said sleeve. Said shaft is telescoped within or extended from said sleeve by means of a wing nut or threaded member 21 threaded thereon and having oppositely extending hand grips 22, 22. Said threaded member is adapted to rest on the collar 18 and a retaining member 23 is herein shown as projecting downwardly from one of the hand grips 22 and extending inwardly of said collar, to prevent upward lifting movement of said threaded member with respect to said collar.

The trough sections 12, 12, as herein shown, are each provided with longitudinally extending channeled guides adjacent opposite sides thereof and intermediate the ends thereof. Said guides, as herein shown, consist of a pair of vertically spaced facing angles 24, 24, with their vertical legs disposed inwardly. Each pair of said angles is secured to opposite side of said trough section 20 by means of a pair of parallel spaced straps 25, 25, secured to the outer sides of the upper flared portion of said trough section in any suitable manner, such as welding. Opposite guides are secured together, to maintain rigidity of said guides, by means of parallel spaced connecting members 26, 26, secured to the bottom of said trough section and connected to opposite lower angles at their ends.

Rollers 29, 29 are provided to support the trough section 12 on the jacks 11, 11. Said rollers are each mounted on a shaft 30 and the upper angles 24, 24 ride thereon, the lower angles serving to prevent upward lifting movement of said trough section. Said shafts, as herein shown, are mounted in sleeves 31, 31, which are mounted in the open ends of a U-frame 33, which serves to hold said shafts rigid with respect to each other and in aligned relationship, to permit alignment of the trough sections where the bottom is uneven, or when the jacks are in various angular relations with respect to each other.

Each sleeve 31 loosely extends through a strap 34, projecting from the lower end of an adjusting member 35, which is slidably mounted on the sleeve 16 of the jack 11. The clearance between said strap and sleeve is sufficient to permit a substantial amount of angular movement of said jack with respect to said shaft, and thus permit accurate alignment of the trough sections, without binding, when the jacks are at various angu-

lar positions with respect to each other and with respect to said shafts, as in cases where the bottom is uneven.

A U-shaped clamping member 36 is provided to secure each shaft 30 and adjusting member 35 in position along the sleeve 16. The ends of said clamping member extend along said opposite sides of the strap 34 and are of a fishtail formation to firmly engage the sleeve 31. Said clamping member is tightened against said sleeve to engage said sleeve with the sleeve 16 and rigidly hold the sleeve 31 and the adjusting member 35 in position on the jacks 11, by means of a nut 37 threaded on the outer end of a stud 38 and engaging the outside of said clamping member. The opposite end of said stud is threaded within the strap 34.

Referring now in particular to the means for adjustably moving the adjusting members 35, 35 along the sleeves 16, 16 and jacks 11, 11, said jacks are each provided with a pair of spaced apart projecting brackets 39, 39, between which is mounted a rod 40. Said rod extends through a pair of spaced apart abutments 43, 43 projecting from the adjusting member 35, and through a friction grip lifting member 44, which is disposed between said abutments and serves to lift said elevating member or permit it to be loosened. A suitable hand lever 45 is pivotally mounted on the lifting member 44 to clamp certain friction means (not shown), mounted within said elevating member, with the rod 40, and move said lifting member upwardly along said rod. Said rod and lifting member are of a construction similar to the well-known form of automobile type friction bumper jack, and are not part of my present invention so need not herein be shown or described in detail.

It may be seen from the foregoing that the shafts 30, 30 and rollers 29, 29 may be adjustably moved along the sleeves 16, 16 by the lifting members 44, 44, to adjust the conveyer trough line 10 in a transverse or vertical direction, and that since substantial clearance is provided between the sleeves 31, 31 and the straps 34, 34, said adjusting mechanism is effective and said shafts may be rigidly held in position when the jacks 11, 11 are parallel spaced or are angularly positioned with respect to each other. It may likewise be seen that the independent adjustment of said shafts along said sleeves permits ready adjustment of the trough line, and that the rollers 29, 29 engaging within the channelled guide formed between the spaced apart angles 24, 24 prevent upward lifting movement of the trough line with respect to said jacks, and the ends of said rollers engaging the vertical legs of said angles serve to hold said trough line in longitudinal alignment.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an

adjustable connection between each of said rollers and its associated jack, permitting adjustable movement of said shafts and rollers along said jacks when said jacks are in various angular positions with respect to the ground including an adjusting member mounted on each of said jacks, for movement therealong, each of said members having a portion for loosely receiving one of said shafts, means engaging each of said members for moving said members vertically along said jacks, and other means for clamping said shafts and members in position on said jacks comprising a clamping member mounted on each of said adjusting members and adapted to positively hold said associated shaft in engagement with its associated supporting jack.

2. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks, for movement therealong, said member having a portion for loosely receiving one of said shafts, means for clamping said shaft and adjusting member in position on said jack, and lifting means mounted on said jack and having engagement with said adjusting member for vertically moving said adjusting member along said jack.

3. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks, for movement therealong, said member having a portion for loosely receiving one of said shafts, means for clamping said shaft and adjusting member in position on said jack, a rod extending along and mounted in parallel spaced relation with respect to said jack at its ends and lifting means mounted on said rod and having engagement with said adjusting member for vertically moving said adjusting member along its associated jack.

4. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks for movement therealong, a strap projecting from said member for loosely receiving one of said shafts, and means engaging said strap

and shaft to hold said shaft and adjusting member in position on said jack when said jack is in various angular positions with respect to the vertical, and said shaft is in a horizontal position.

5. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks for movement therealong, a strap projecting from said member for loosely receiving one of said shafts so said jack and adjusting member may be held in position on said shaft, when said jack is in various angular positions with respect to the vertical, and said shaft is in a horizontal position, and means for clamping said shaft in engagement with said jack including a clamping member adapted to engage said shaft on opposite sides of said strap.

6. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks for movement therealong, a strap projecting from said member for loosely receiving one

10 of said shafts so said shaft and adjusting member may be held in position on said jack when said jack is in various angular positions with respect to the vertical and said shaft is in a horizontal position, and means for clamping said shaft in engagement with said jack including a clamping member adapted to engage said shaft on opposite sides of said strap, and means secured to said strap and engaging said clamping member for clamping said shaft to said jack.

15 7. In a trough support for shaker conveyers, a pair of spaced apart supporting jacks adapted to be interposed between a mine roof and floor, a trough supporting roller mounted on each of said jacks, shafts on which said rollers are mounted, a member extending beneath said trough for connecting said shafts in aligned relationship, and an adjustable connection between each of said rollers and its associated jack, permitting adjustable movement of said shafts and rollers along said jacks when said jacks are in various angular positions with respect to the ground including an adjusting member mounted on each of said jacks for movement therealong, a strap projecting from said member for loosely receiving one of said shafts so said shaft and adjusting member may be held in position on said jack when said jack is in various angular positions with respect to the vertical and said shaft is in a horizontal position, and means for clamping said shaft in engagement with said jack including a clamping member adapted to engage said shaft on opposite sides of said strap, and means secured to said strap and engaging said clamping member for clamping said shaft to said jack, a rod extending along and mounted in parallel spaced relation with respect to said jack at its ends, and lifting means mounted on said rod and having engagement with said adjusting member for vertically moving said adjusting member along its associated jack,

WILLIAM W. SLOANE.

CERTIFICATE OF CORRECTION.

Patent No. 2,239,578.

April 22, 1941.

WILLIAM W. SLOANE.

It is hereby certified that error appears in the printed specification of the above numbered patent requiring correction as follows: Page 3, first column, line 20, claim 5, for the word "jack" read --shaft--; line 21, same claim, for "shaft" read --jack--; and that the said Letters Patent should be read with this correction therein that the same may conform to the record of the case in the Patent Office.

Signed and sealed this 3rd day of June, A. D. 1941.
